UNITED STATES PATENT OFFICE.

ALBERT STEINER, OF CINCINNATI, OHIO.

DESIGN FOR A CAKE OF SOAP OR SIMILAR ARTICLE.

53,537.

Specification for Design.

Patented July 8, 1919.

Application filed February 27, 1919. Serial No. 279,642. Term of patent 14 years.

To all whom it may concern:

Be it known that I, ALBERT STEINER, a citizen of the United States, residing at Avondale, Cincinnati, in the county of Hamilton and State of Ohio, have invented a new, original, and ornamental Design for a Cake of Soap or Similar Article, as shown in the accompanying drawing, in which—

Fig. 2 an end view thereof.

I claim:

The ornamental design for a cake of soap or similar article as shown.

ALBERT STEINER.

Witnesses:

CHARLOTTE M. BRAUN,
ELLA G. ZELLER.
